US0D1037343S

(12) **United States Design Patent** (10) **Patent No.:** **US D1,037,343 S**
(45) **Date of Patent:** **** Jul. 30, 2024**

(54) **EYEGGLASSES**

(71) Applicant: **Oakley, Inc.**, Foothill Ranch, CA (US)

(72) Inventors: **Duong Bang Le**, West Covina, CA (US); **Nicolas Adolfo Garfias**, Long Beach, CA (US)

(73) Assignee: **Oakley, Inc.**, Foothill Ranch, CA (US)

(**) Term: **15 Years**

(21) Appl. No.: **29/855,791**

(22) Filed: **Oct. 7, 2022**

(51) **LOC (14) Cl.** **16-09**

(52) **U.S. Cl.**

USPC **D16/335**

(58) **Field of Classification Search**

USPC 2/426-432, 435, 436, 437, 438, 439, 2/440-454; 351/43, 44-47, 49, 59, 63, 351/69, 104, 123, 126, 131, 132, 135, 351/145; D16/101, 300-342

(57) **CLAIM**

The ornamental design for eyeglasses, as shown and described.

DESCRIPTION

FIG. 1 is a top front perspective view of eyeglasses showing the claimed design;

FIG. 2 is a front elevation view thereof;

FIG. 3 is a rear elevation view thereof;

FIG. 4 is a right side elevation view thereof, the left side elevation view being a mirror image thereof;

FIG. 5 is a top view thereof; and,

FIG. 6 is a bottom view thereof.

The broken lines in the figures show portions of the eyeglasses that form no part of the claimed design.

1 Claim, 6 Drawing Sheets
